UNITED STATES PATENT OFFICE.

WILLIAM V. RAFFERTY, OF PROVIDENCE, RHODE ISLAND, ASSIGNOR TO GENERAL CHAIN COMPANY, OF PROVIDENCE, RHODE ISLAND, A CORPORATION OF MASSACHUSETTS.

CHAIN-CURBING MACHINE.

Application filed January 30, 1920. Serial No. 355,163.

To all whom it may concern:

Be it known that I, WILLIAM V. RAFFERTY, a citizen of the United States, and resident of the city of Providence, in the county of Providence and State of Rhode Island, have invented certain new and useful Improvements in Chain-Curbing Machines, of which the following is a specification.

10 This invention relates to curb-chain twisting or resetting machines of the class adapted to return a curb chain or reset the curb or twist in a chain to its normal twist or position after the individual links have 15 been reformed or unified.

In practice after the chain has been curbed it is usually left somewhat uneven due to irregularities in the temper of the stock and in the action of the machine forming the links. The effects of these irregularities in the individual links are subsequently removed by passing the chain through hammers or rolls to render the links absolutely uniform in size and shape. This 20 25 30 35 40

The object of this invention is to restore this initial curb or twist in the chain, which is done by drawing the chain through two guide or draw plates, each having an eye or slot, that fits the chain, placed at an angle to each other, so that when the chain is drawn through both, it is twisted, and set or turned back sufficiently so that when free it will hang perfectly straight and not present that twisted or warped appearance.

With these and other objects in view, the invention consists of certain novel features of construction, as will be more fully described, and particularly pointed out in the 45 appended claims.

In the accompanying drawings:

Figure 1—is a side elevation partly in section, showing my improved chain-twisting or curb-resetting machine.

50 Figure 2—is a detail in perspective illustrating the worm gearing means for setting the chain slot in one of the guide plates at an angle relative to that of the other.

Figure 3—is a sectional side elevation

through the head containing the chain-guide plates.

Figure 4—is an end view of the head, illustrating the rotatable adjustable mechanism.

Figure 5—is a top view of the head, illustrating the graduations by means of which the exact setting of the plates both towards and from each other and circularly, may be determined.

Figure 6—is a detail of one of the guide or die plates.

Figure 7—shows a piece of curb chain enlarged.

With reference to the drawings, 10 designates one form of frame of my improved 70 machine, which may be supported on legs 11 and on this frame I have mounted a pair of feed rolls 12 and 13; roll 12 being fixedly mounted on shaft 14 on the outer end of which shaft I mount a power-transmitting 75 pulley which may be driven through the belt 16 or by hand if desired.

The tension roll 13 is mounted on a shaft 17 in sliding bearing blocks 18 in the slot 19, springs 20 being provided to press these 80 bearings inwardly so that the roll 13 will grip the chain 11 against the main feed-roll 12, to draw the chain forwardly through the gripping head 22 from the reel 23. A handle is provided by which this roll 13 may 85 be withdrawn from engagement with roll 12 to permit the chain to be passed therebetween.

The chain-twisting head is preferably mounted on the standard 24 supported from 90 the base 10 in which head I have mounted a curbing guide plate 25 which is provided with an elongated or somewhat rectangular, central hole, eye or opening 26 adapted to fit the chain 27. This plate is held in position 95 in the head by means of the binding screw 28.

A second guide or curbing plate 29 is held in the adjustable cup-shaped bearing member 30 by means of the set screw 31. 100 This cup-shaped bearing member is adapted to be adjusted both in and out so as to regulate the space between these guide plates 25 and 29, which regulating is of importance in determining the twist which shall be imparted or set in the chain as it is drawn through these plates.

In order to obtain this in and out adjust-

ment, I first lessen the binding screw 32 then by setting up the screws 33 I withdraw the bearing member with its plate 29, the extent of movement being determined by the 5 graduations on the tongue 34.

After reaching the desired position I again tighten the set screw 32.

In order to obtain the second adjustment by which the correct amount of curbing or 10 twisting of the chain is also determined I rotate this bearing member 30 with its guide plate 29 so as to bring the major axis of its center opening 35 at the proper angle relative to the major axis of the opening 26 in 15 the fixed plate 25.

To accomplish this in a simple and practical way I have formed a ring 36 whose lower edge is provided with teeth as at 37, which teeth are engaged by a worm 38 and 20 I have mounted on this ring a finger 34 which extends forwardly through a slot 39 in the flange 40 of this bearing member 30 whereby a rotating movement of this worm 38 by its knurled head 41 causes a rotation 25 of this bearing member 30 with its plate 29 setting its opening 35 at the proper angle to that of opening 26 in the opposite plate.

The guide openings 26 and 35 are shown as being substantially elongated, that is 30 having a greater diameter in one direction, but these openings may be of any size or shape as will permit the linkings of the chain to pass therethrough but which will prevent the links from turning axially in 35 the openings.

When it is desired to rotate this bearing member 30 with its plate 29 quickly it is only necessary to press the operating handle 41 of the worm 38 downwardly whereby 40 the bearing block 42 in which the screw is mounted will swing on its pivot 45 downwardly against the tension of the spring 46 thereby releasing this bearing member 30 to be rotated independently of the worm and 45 as soon as this handle is released the worm returns into engagement with the toothed portion 37 of the member 40.

After the plate 29 has been set in exactly the proper position to obtain the desired result 50 on the chain the set screw 32 is turned up by its handle 47 to securely bind and hold it in its set position.

It is to be understood that in the curbing operation of the chain by the present machine the relative spacing of the plates 25 and 29 may be adjusted to obtain the best results as can be determined by those skilled in the art. However, the spacing of these plates is less than the length of the links 60 of the chain being operated upon, although in some instances this may not be necessary.

By the use of my improved machine instead of being obliged to operate upon the chain by hand to re-set or re-curb a chain 65 after it has passed through the hammers or

rolls, it is only necessary to draw the same through my guide or resetting plates and the chain will come out in a perfectly curbed condition.

The device is extremely simple and practical in construction and effective in its operation and by its use the curbing or resetting of the twist in the chain may be readily and accurately accomplished. 70

The foregoing description is directed 75 solely towards the construction illustrated, but I desire it to be understood that I reserve the privilege of resorting to all the mechanical changes to which the device is susceptible, the invention being defined and 80 limited only by the terms of the appended claims.

I claim:

1. In a machine of the character described, a pair of relatively fixed plates 85 having guide openings therein permitting the passage of chain links therethrough and preventing the links from turning axially therein, means for holding said guide plates in close spaced apart relation, one having the major axis of its guide opening set in a relatively different position to that of the other, the distance between said plates being substantially the length of one link of the chain being operated upon whereby the 95 chain links are subjected to a curbing operation when passing through said guide openings.

2. In a machine of the character described, a pair of relatively fixed plates 100 having guide openings therein permitting the passage of chain links therethrough and preventing the links from turning axially therein, means for holding said guide plates in close spaced apart relation, one having the major axis of its guide opening set in a relatively different position to that of the other, the distance between said plates being substantially the length of one link of the chain being operated upon whereby the 105 chain links are subjected to a curbing operation when passing through said guide openings, and means for drawing the chain through said plates to set a twist therein.

3. In a machine of the character described, a pair of guide plates each having an elongated opening therethrough, said 115 two openings being substantially in register, and means whereby said plates may be adjusted to position said guide openings 120 therein with their major axes at different angles relative to each other and to regulate their relative angularity, whereby the chain links are subjected to a curbing operation when passing through said guide openings. 125

4. In a machine of the character described, a holder for a pair of chain guide plates, each of said plates having a guide opening to fit the contour of the links, one 130 of said openings being set at an angle to

that of the other, means whereby one of said plates may be rotated to adjust the operating angle of its opening relative to that of the other, means for drawing chain 5 through said plates to set the twist therein, and means for locking said plates in adjusted position.

5. In a machine of the character described, means for holding two cooperating 10 chain guide plates in close spaced relation, each plate having a slotted chain guiding opening therein, said two openings being substantially in register, a worm gearing means, whereby said plates may be adjusted 15 for setting the slotted openings therein to extend at different directions and to change the relative operating angularity of said openings for regulating the amount of twist to be fed to the links in the chain as it is 20 drawn therethrough.

6. In a machine of the character described, two cooperating chain guide plates, means for holding said guide plates, each having a chain guiding opening therein substantially in register with the opening in 25 the other plate, worm-gearing means whereby said plates may be adjusted for setting the slotted openings thereof to extend in different directions and to change the relative operating angularity of said slotted 30 openings to regulate the amount of twist to be set in the links in the chain as it is drawn therethrough, and means for securing said plates in adjusted position.

35 7. In a machine of the character described, a chain curbing mechanism including a pair of opposed members having guide openings therein through which the links of chains may pass and which will prevent 40 axial turning of the links therein, means for adjusting the relative distances between said members, and means for positioning the guide openings in said members in different relative positions, whereby the links of 45 chains passing through the openings will be curved.

8. In a machine of the character described a curbing device including relatively fixed plates having slotted openings therein 50 positioned relative to each other to produce a curbing operation on each chain link as the chain is drawn therethrough.

9. In a chain curbing machine, a twisting head having a stationary die unit thereon 55 provided with a chain guiding opening, a second die unit having a chain guiding opening therein and mounted in the head for a rotating and slidable movement, a rotatable member mounted on said head having 60 gear teeth and a projection extending through a slot in said second die unit, a worm engageable with the teeth of said rotatable member, whereby said second die unit may be rotated relative to said first die

unit, and adjusting means for varying the 65 slidable movement of said second die unit relative to said first die unit whereby the distance between said units may be varied.

10. In a chain curbing machine, a twisting head having a stationary die unit thereon provided with a chain guiding opening, a second die unit having a chain guiding opening therein and mounted in the head for a rotating and slidable movement, a rotatable member mounted on said head having 70 gear teeth and a projection extending through a slot in said second die unit, a worm engageable with the teeth of said rotatable member, whereby said second die unit may be rotated relative to said first die 75 unit, an adjustable means for varying the slidable movement of said second die unit relative to said first die unit whereby the distance between said units may be varied, said worm being shiftable from engagement with the teeth of said rotatable member and means for yieldingly maintaining said worm in engagement with said teeth.

85 11. In a chain curbing machine, a twisting head having a stationary unit thereon having a guiding plate mounted therein with a chain guiding opening therethrough, a second unit having a chain guiding plate mounted therein provided with a guiding 90 opening to substantially register with the opening in the plate of said first unit, said second unit being mounted in said first unit and having a rotatable movement and a sliding movement toward and away from the plate of said first unit, an annulus surrounding said second unit and rotatably mounted on said first unit, a lateral projection extending from said annulus and extending through an opening in said second 95 unit, whereby said second unit will be rotated with said annulus but free for a sliding movement toward and away from said first unit, and a worm mounted on said first unit for engaging with teeth on said annulus, and means for adjusting the slidable movement of said second unit.

100 12. A curbing machine comprising a frame, a reel on the frame for supporting chain to be curbed, a pair of feed rolls, one 105 of which is stationarily journaled on the frame, the other being mounted to move toward and from said first roll, means for yieldingly maintaining said shiftable roll in engagement with said first roll, means for 115 manually moving said shiftable roll out of engagement with said first roll, and means for driving said stationary roll whereby said chain is fed through the machine, and a curbing head interposed between said reel 120 and rolls.

In testimony whereof I affix my signature.
WILLIAM V. RAFFERTY.
